Patented Nov. 25, 1902.

H. F. W. MOHR.

ADJUSTABLE MAIL DISTRIBUTING CASE.

(Application filed June 7, 1902.)

(No Model.)

UNITED STATES PATENT OFFICE.

HENRY F. W. MOHR, OF TOLEDO, OHIO.

ADJUSTABLE MAIL-DISTRIBUTING CASE.

SPECIFICATION forming part of Letters Patent No. 714,220, dated November 25, 1902.

Application filed June 7, 1902. Serial No. 110,569. (No model.)

To all whom it may concern:

Be it known that I, HENRY F. W. MOHR, a citizen of the United States, residing at Toledo, in the county of Lucas and State of Ohio, have invented certain new and useful Improvements in Adjustable Mail-Distributing Cases; and I do hereby declare the following to be a full, clear, and exact description of the invention, such as will enable others skilled in the art to which it appertains to make and use the same.

My invention has reference to an adjustable mail-distributing case, and has for its object to provide a case of this character in which are provided simple and easily-operated shelves, whereby the sizes of the pockets of the case may be varied. In the old form of mail-distributing case at present in general use the pockets are all of uniform size and capacity, so that at times it becomes necessary to utilize two or more separate pockets to receive the mail directed to a single post-office, whereas the mail directed to another post-office may be of sufficient quantity to only partly fill one of the pockets.

In carrying out my invention I provide a novel construction whereby sheet metal, preferably sheet-steel, may be employed in building the case, and the same will be comparatively light in weight considering the nature of the material employed, exceedingly strong, easily kept clean, and consequently sanitary. Since metal may be exclusively employed in the construction of my improved case, the same will be fireproof, which fact makes the case valuable for employment in post-offices where it is desired to reduce the danger from fire to a minimum.

In carrying out my invention I employ certain novel features of construction and the arrangement hereinafter shown, described, and claimed.

In the drawings, Figure 1 is an elevation showing the upper left-hand section of a case embodying my improved construction. Fig. 2 is a vertical section through the case, one of the shelves being in position. Fig. 3 is a transverse section through the case, showing the corrugations in the vertical partitions and the side walls of the case. Fig. 4 is a top plan view of one of the shelves. Fig. 5 is a bottom plan view of one of the shelves. Fig. 6

is a broken plan view showing the means for supporting the shelves between the vertical partitions.

55

The sides, top, and bottom of the case constituting the main frame 1 are preferably formed from a single length of sheet metal, the ends being suitably joined together by riveting or otherwise. Arranged, preferably, at equal distances apart, with their upper and lower ends riveted or otherwise secured to the top and bottom of the case, are vertical sheet-metal partitions 2, between which are supported the removable shelves 3. The side walls of the case and also the vertical partitions are provided with longitudinally-extending corrugations 4. As shown in the drawings, these corrugations are S-shaped. The adjustable shelves comprise a flat rectangular sheet-metal table-section 5, adapted to be inserted between the vertical partitions 2, the side margins at 6 having a configuration coincident with the form of the corrugations 4. Upon the lower face of the shelves 75 are provided slidable locking-bolts 7, the ends 8 of which project laterally beyond the sides of the shelves and are adapted to enter perforations provided lengthwise of the vertical partitions. The locking-bolts are in the form of U-shaped rods 9, the arms 7 of which 80 form the bolts proper, being guided laterally through downwardly-extending lugs 10, stamped from the body of the table-section of the shelves.

85

11 represents springs suitably secured adapted to engage the U-shaped rods 9 and spring the bolts outward. The bolts are retracted by pressing the U-shaped rods together. The locking-bolts are each provided near their outer ends with a transverse pin 12, the bolt extending beyond the pin a distance equal to the thickness of the metal forming the vertical partitions. The bolts will therefore enter the perforations in the vertical partitions 95 and maintain the shelves in position, and the same will, however, be held, on account of the transverse pins, from extending through the partitions into an adjoining pocket of the case. If the ends of the bolts were permitted to extend through the vertical partitions into the pockets of the case, the envelope upon being deposited in the pockets would strike the same and be damaged. If the bolts upon

95

100

opposite sides of the shelf-supports were arranged in exact alinement with each other, it is apparent that the bolts upon opposite sides of adjoining shelves would enter the 5 same perforation. This would be the case only where both shelf-supports have the same elevation, as at *a a*, Fig. 1. In order that the bolts may enter the perforations provided to receive the same and so that the same will 10 not interfere with each other in their operation, I have arranged those upon one side of the shelf-supports out of alinement with those upon the opposite side. The perforations *b b* are adapted to receive the ends of the 15 bolts extending on one side of the shelf-supports, and the perforations *c c* those extending from the opposite side. By this arrangement the bolts will take positions alongside of each other, and will engage the perforations 20 without coming into contact.

13 is a wire screen arranged across the back of the case, being secured to the rear margins of the main frame, and the same is adapted to retain the mail-matter in the pockets 25 and prevent its falling out of the back of the case. As the shelves fit snugly between the vertical partitions and since the portions 6, adapted to enter the corrugations provided upon the partitions, extend on either side of 30 the body of the same, it is apparent that the shelves must be tilted in placing them in position. After being in position the same will be firmly held from forward or backward movement and the bolts will be guided directly into the perforations. It is apparent 35 that the case is materially strengthened by providing the corrugations upon the vertical partitions and that as a consequence very thin sheet metal may be employed in their 40 construction. Although I have described the vertical partitions as being formed with corrugations of specific shape and the table-sections of the shelves having engaging portions coincident with said corrugations, I do not 45 wish to confine myself to any exact form of corrugation, since it is apparent that the form of the same may be varied. The vertical partitions may, if desired, have a plurality of corrugations arranged parallel to each other 50 and the side margins of the shelves may be formed coincident therewith.

From the foregoing it is observed that the

shelves are easily inserted between the vertical partitions of the case at any desired point and that the capacity of the pockets therein 55 may be varied at the pleasure of the user.

The novelty and utility of my invention are apparent.

Having described my invention, what I claim, and desire to secure by Letters Patent, 60 is—

1. In a mail-distributing case, a main frame, the vertical partitions secured within the main frame having longitudinal corrugations and provided with spaced perforations, in 65 combination with detachable shelves having lateral marginal edges coincident in shape to the vertical partitions, the same also being provided with spring-actuated bolts adapted to enter the perforations in the vertical partitions, as set forth. 7c

2. In a mail-distributing case, a sheet-metal main frame, the sheet-metal vertical partitions secured within the main frame provided with longitudinal corrugations and spaced 75 perforations, in combination with detachable shelves each having a sheet-metal table-section, the marginal edges of which are coincident in shape to the vertical partitions, and having spring-actuated bolts extending on 80 opposite sides of the table-section adapted to enter the perforations in the vertical partitions, those on one side of the table-section being out of alinement with those of the other, as set forth. 85

3. In a mail-distributing case, the sheet-metal main frame, the sheet-metal partitions secured within the main frame provided with longitudinal corrugations and having the perforations *b b* and *c c*, the shelves having 90 a sheet-metal table-section formed at 6 coincident to the shape of the corrugations provided upon the partitions, and having the downwardly-extending lugs 10, the bolts 7 extending therethrough, the springs 11 adapted 95 to actuate the bolts, and the transverse pins 12 provided at the ends of the bolts 7, all arranged to operate as set forth.

In testimony whereof I hereunto affix my signature in presence of two witnesses.

HENRY F. W. MOHR.
